Patented Aug. 29, 1922.

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

1,427,689.

Specification of Letters Patent. Patented Aug. 29, 1922.

Application filed October 7, 1919. Serial No. 329,014.

To all whom it may concern:

Be it known that I, ALFRED G. F. KUROWSKI, a citizen of the United States, formerly a citizen of Germany, residing in Brooklyn borough, in the county of Kings, city and State of New York, have invented certain new and useful Improvements in Type-writing Machines, of which the following is a specification.

10 This invention relates to devices for clamping cards or work-pieces to a cylindrical platen. An object of the invention is to provide a simple and effective means, whereby cards or work-pieces of various 15 widths may be clamped on the platen without requiring any special adjustment of the clamping means.

According to the present invention, a resilient clamping plate, preferably of sheet-metal, is secured to the platen, near one edge, 20 and is shaped to conform closely to the contour of the platen. Due to the resiliency of the clamping plate, it may serve to clamp to the platen a card or work-member, inserted 25 beneath the free edge of said clamping plate, when the latter is raised from the platen.

Provision is also made of paper-stops, 30 preferably in the form of pins, secured to the resilient plate near its clamping edge, and of an edge-guide, preferably in the form of a tongue cut from the metal of said plate, adjacent its edge, and turned to a position substantially at a right angle with said plate. The paper-stops and the edge-guide project into suitable depressions in the platen. By virtue of this construction the clamping plate, paper-stops and edge-guide may all be attached to, or removed 35 from, the platen simultaneously.

40 Provision is also made of means to control the effective or ineffective position of the clamping plate. For this purpose, a camming shaft, which serves to control the position of the clamping plate, is pivotally supported at one end in the closed end of a trough-shaped member, secured in a depression in the platen, and is pivotally supported at the other end in a bracket, secured to the head of the platen, the camming shaft, 45 when in normal position, being substantially flush with the surface of the platen, but projecting therefrom when turned to lift the clamping plate.

For the purpose of controlling the camming shaft, a finger-piece is connected there-

with, and means are provided for limiting the movement of the finger-piece with reference to the adjacent bracket.

Other features and advantages will hereinafter appear.

In the accompanying drawings,

Figure 1 is a perspective view, showing a platen, with my invention applied thereto, the platen being broken away to show the underlying structure.

Figure 2 is a perspective view of the parts of the device for controlling the card-holder.

Figure 3 is a fragmentary perspective view, showing the left end of the clamping plate.

Figure 4 is an end view, showing the clamping plate lifted to permit insertion of the card.

Figure 5 is a view similar to Figure 4, but with the clamping plate in effective position, 75 and with the platen turned to bring the card, clamped thereon, to position for cooperation with the type-bars.

The platen 1, of the usual type, comprises a surface layer 2, of rubber or other suitable 80 material, mounted on a hollow wooden cylinder or core 3, which is supported by means of heads 4, on an axle 5. Said axle 5 is journaled in end-frames 6 of the platen-frame, and is provided, at its ends, with finger-wheels 7, only one of which is shown.

At the left end of the platen-frame, a line-space-ratchet-wheel 8 is secured to said axle 5, the ratchet-wheel-actuating pawl 9 and the slide 10, on which it is pivoted, being indicated in dot-and-dash lines on Figure 1.

The card-holder proper consists of a resilient plate 11, provided, at its forward edge, with a flange portion 12, which is inserted in a kerf or slot in the platen, the clamping 95 plate being secured to the platen by screws 13. The width of the cards being usually less than the length of the platen, a clamping plate, less in length than the cylinder, is provided. Said plate 11 follows closely the 100 contour of the platen surface, and its free edge serves to press against the platen a card placed thereunder. In order to prevent the work from being inserted too far under said clamping plate 11, provision is made of pins 105 14, fixed in said plate near its clamping edge, the platen being provided with suitable recesses to receive the pins. Near the left end of said plate 11, a tongue 15 is formed by a cut normal to the clamping 110

edge and a cut parallel thereto. The tongue 15, thus formed, is turned downwardly from the plate 11, to serve as an edge-guide, and projects into a suitable recess provided in 5 the platen.

In order to lift the clamping edge of plate 11, to permit the insertion of a card thereunder, use is made of a camming shaft or cam-rod 16, having a flattened face 17, the 10 cross-section of said shaft 16 being in the form of a segment of a circle. The reduced inner end 18 of shaft 16 is mounted in a bearing formed in the closed inner end of a trough-shaped member 19, secured in any 15 suitable manner in a groove or depression in the platen; and a reduced portion 20, at the outer end of said shaft 16, is supported in a bearing in a bracket 21, attached to the platen-head by screws 22 or other suitable 20 means. The shoulders at the ends of the reduced portions 18 and 20 of shaft 16 engage with the bearings, and prevent longitudinal movement of the shaft. It will be seen that when the flat face 17 of the camming shaft 25 is turned outwardly, it will be substantially flush with the surface of the platen, and will permit the clamping plate 11 to lie close to the surface of the platen, but that, when the shaft 16 is turned from its normal position, 30 the plate 11 will be pressed outwardly, to permit a card to be inserted thereunder. Upon turning the camming shaft back to its normal position, after such insertion, the card will be clamped to the platen. 35 For the purpose of controlling the movement of the camming shaft 16, a finger-piece 23 is secured to the reduced outer end 20 of shaft 16. A pin 24, mounted in the finger-piece 23, projects into an arcuate slot 25 in bracket 21, thus providing means for limiting the movement of the finger-piece with 40 reference to the bracket. Upon reference to Figure 5, it will be seen that finger-piece 23, when in its normal position, does not interfere with the rotation of the platen. 45

When a card is to be inserted, the platen is turned to the position shown in Figure 4, and finger-piece 23 is moved from the position shown in Figure 5 to that in Figure 4, 50 thus raising the clamping edge of plate 11 sufficiently to permit insertion of a card 26. The finger-piece 23 is then returned to its normal position, shown in Figure 5, and the platen turned, to carry the clamping plate 55 and card over the usual pressure-feed-rollers 27 and 28, to the position shown in Figure 5, to enable type-bars 29 to print thereon. It will be seen that the clamping device so 60 nearly coincides with the platen surface that no difficulty is experienced in feeding the cards or work-sheets, engaged by said clamping device, past the feed-rollers 27 and 28. The card may then be advanced by means of finger-wheels 7, or by the line-space-pawl 9, 65 while typewriting on said card, and the

platen may then be turned forwardly, and, upon completion of the typewriting, the card may be released by manipulation of the finger-piece 23.

Variations may be resorted to within the 70 scope of the invention, and portions of the improvements may be used without others.

Having thus described my invention, I claim:

1. The combination with a platen, of a 75 resilient plate secured thereto, and having one edge pressing against said platen to clamp a work-member thereagainst, and means to control the position of the clamping edge of said plate, comprising a cam-member pivotally supported at one end of said platen and normally flush with the surface of the platen, and at a point intermediate the ends of said platen, said cam-member lying in a depression in said platen, 80 and being so formed that when turned from its normal position, it will be effective to engage said plate, and move the clamping edge to ineffective position.

2. The combination with a cylindrical 90 platen, of a resilient clamping plate extending from one end of the platen to a point intermediate the ends thereof, and controlling means for said clamping plate, comprising a camming shaft, and a trough-shaped 95 member in said platen, said member being open at its outer end and closed at its inner end, said camming shaft being pivoted in the inner end of said trough-shaped member, and supported on the platen-head, adjacent the open end of said trough.

3. The combination with a cylindrical platen, of a resilient clamping plate extending from one end of the platen to a point intermediate the ends thereof, and controlling means for said clamping plate, comprising a trough-shaped member set in a 105 recess in said platen, underlying said clamping plate, said trough-shaped member being closed at its inner end, a bracket on the head 110 of said platen, adjacent the open end of said trough-shaped member, and a camming shaft in said trough-shaped member pivoted in the closed end thereof and in said bracket.

4. The combination with a platen, comprising a head, of a clamping plate secured at its forward edge to said platen, and extending from said head to a point intermediate the ends of said platen, paper-stops and an edge-guide on said plate, and controlling means for said plate.

5. The combination with a platen, comprising a head, of a clamping plate, extending from said head along a part of the length of said platen, and controlling means for said plate, comprising a trough-shaped member underlying said plate in a depression in said platen and closed at its inner end, a bearing in the closed inner end of said trough-shaped member, a bracket se- 120 125 130

- cured to said head, and provided with a bearing in alignment with the first-mentioned bearing, a camming shaft mounted in said bearings, and adapted to engage said 5 plate, and render the same ineffective, and a finger-piece mounted on said camming shaft, for operating the same.
6. The combination with a platen, comprising a head, and having a groove extending from said head to a point intermediate the ends of said platen, of a resilient clamping plate overlying said groove, a bearing secured in said groove at its inner end, a bearing on said head in alignment with said 10 first-mentioned bearing, and a camming device mounted in said bearings, the rotative position of said camming device being determinative of the effectiveness of said clamping plate.
- 15 7. The combination with a platen, comprising a head, of a clamping plate extending along part of the length of said platen, a bearing secured to said platen, under the inner end of said plate, a bracket supported
- on said head, a camming shaft supported in 25 said bearing and journaled in said bracket, a finger-piece for controlling said shaft, and co-operative devices on said bracket and said finger-piece, to limit the movement of the latter.
- 30 8. The combination with a platen, of a resilient plate secured thereto, and having one edge pressing against said platen to clamp a work-member thereagainst, and means to control the position of the clamping edge of said plate comprising a cam-member pivotally supported in a lengthwise depression in said platen and normally flush with the surface of the platen, and being so formed that when turned from its normal 35 position it will be effective to engage said plate and move the clamping edge to ineffective position.
